UNITED STATES PATENT OFFICE

FRANK YOUNG, OF LOGANSPORT, INDIANA

RIDGE ROLL

Application filed April 14, 1930. Serial No. 444,311.

The object of the invention is to provide means for capping the ridge of a roof covered with asphalt or composition shingles, so as to avoid the use of the metal strip ordinarily employed for this purpose with its tendency to discolor the shingles by reason of rust; to provide a ridge roll of the general nature of an asphalt or composition shingle but which includes a metallic reinforcement permitting its being shaped to and retaining its seat upon the ridge, the roll being colored in accordance with the shingles in connection with which it is used; and to provide an article of manufacture of this nature which is of simple form and susceptible of cheap manufacture and low marketing cost.

With this object in view, the invention consists in a construction and combination of parts of which a preferred embodiment is illustrated in the accompanying drawing, wherein:

Figure 1 is a perspective view of a section of a ridge roof showing the invention applied in operative position.

Figures 2 and 3 are sectional views on the planes indicated by the lines 2-2 and 3-3 respectively of Figure 1.

It is customary, where roofs are covered with composition shingles such as those indicated at 10 to cap the ridge 11 with a piece of sheet iron which must necessarily be kept well painted to protect it; and even in such cases, the rust produced by the elements will find its way upon and discolor the shingles.

The present invention contemplates covering the ridge 11 with a roll of the same general nature as the shingles and consisting of a transversely arched metallic reinforcing plate 12 which may be and preferably is of ordinary sheet iron which is cheap as well as pliable. The reinforcement on the inner face is covered with the composition 14 and on the outer face with the composition 15 of the same general nature as the composition 14, but colored in accordance with the shingles 10. The composition on both faces of the reinforcement is of the same general nature as the composition of the shingles 10.

The reinforcing member being pliable, the roll may be readily shaped to the ridge and, at its longitudinal edges, is turned down, as indicated at 16, to make contact with the adjacent rows of shingles. 55

The sections of the roll are formed for lap-joint connection, the composition 15 being omitted from the reinforcement at one end, as indicated at 17, and the composition 14 being omitted at the other end, as indicated at 18. Thus adjacent sections may be connected at their ends by overlapping the exposed portions of the reinforcements. 60

By means of the invention, the ridge of the roof is made of the same general character as the shingled portions and the ridge, having been once trimmed, requires no further attention, as for example, painting to maintain it in condition, as where sheet iron is used, this materially reducing the cost 70 of upkeep. 65

The invention having been described, what is claimed as new and useful is:

A strip for covering the ridge of a shingled roof and the like comprising a pliable metallic reinforcement of a character to be readily bent to shape, and a roofing composition applied on opposite sides thereof to cover substantially the entire surface area of both sides, the composition on one side being omitted from one face of the reinforcement for the full breadth thereof and for a distance back from the end an amount equal to the overlap of adjacent strips, the composition on the opposite side being omitted from a corresponding area at the opposite end of the reinforcement. 75 80 85

In testimony whereof I affix my signature.

FRANK YOUNG.
